INVENTOR.
J. A. AUBOL,
BY Jerry A. Matthews
ATTORNEY.

UNITED STATES PATENT OFFICE

JULIUS A. AUBOL, OF MINOT, NORTH DAKOTA

GAMBREL

Application filed May 27, 1930. Serial No. 456,166.

My invention relates to improvements in gambrels for supporting meat.

An important object of the invention is to provide a gambrel which is adapted to properly support a carcass from the hook carrying arms when they are in the open position, and which is collapsible so that the hook carrying arms may assume substantially vertical positions, whereby separate sections of beef or the like may be applied to or removed from the two hooks without the gambrel tilting, as would occur if the arms remained in the open position.

A further object of the invention is to provide a device of the above mentioned character which is collapsible into a compact form, and which is of simple construction and is strong and durable.

Other objects and advantages of the invention will be apparent during the course of the following description.

In the accompanying drawings, forming a part of this specification, and in which like numerals are employed to designate like parts throughout the same,

Figure 1 is a side elevation of a gambrel showing the same open,

Figure 2 is an edge elevation of the same,

Figure 3 is a horizontal section taken on line 3—3 of Figure 1,

Figure 4 is a side elevation of the gambrel collapsed, and,

Figure 5 is a detailed section taken on line 5—5 of Figure 3.

In the drawings, wherein for the purpose of illustration, is shown a preferred embodiment of my invention, the numeral 10 designates arms provided at their lower ends with hooks 11, which face outwardly and are bent upwardly. At their upper ends, the arms 10 have apertured knuckles 12, which are offset laterally with respect to the arms 10, so that these arms are positioned in the same plane. The apertured knuckles 12 receive a pivot element or bolt 13, pivotally supported by a link 14.

The numeral 15 designates an adjustable brace arm, formed in sections 16 and 17. These sections 16 and 17 have a knee joint pivotal connection, which breaks down-

wardly, and to accomplish this, the section 17 is provided with a laterally and upwardly extending apertured knuckle 18, arranged between laterally and upwardly projecting knuckles 19, carried by plates 20. These plates are disposed upon opposite sides of the section 16 and rigidly attached thereto by rivets 21 or the like, and project beyond the free end of the section 16. These apertured knuckles 18 and 19 are pivotally connected by means of a bolt or pivot element 22, as shown. The section 17 has a transverse aperture 23, to register with transverse apertures 24, formed in the ends of the plates 20, and these apertures are adapted to receive a locking pin 25, carried by a flexible element or cord 26, secured to one arm 10, as shown. The outer end of the brace arm section 16 is forked, and is provided with apertured knuckles 27, receiving therebetween an apertured knuckle 28, formed upon the intermediate portion of the adjacent arm 10, and these apertured knuckles are pivotally connected by a bolt or pivot element 29. The outer end of the brace arm section 17 is tapered longitudinally, and is provided at its reduced free end with a transverse notch 30, adapted to receive or embrace the adjacent arm 10. Inwardly projecting shoulders or lugs 31 are formed upon the adjacent arm 10 and the wall of the notch engages over a selected shoulder 31.

The operation of the device is as follows:

When the arms 10 are in the open or distended position, the brace arm 15 locks the same in such position, and the pin 25 is held within the apertures 23 and 24 to prevent the downward breaking of the knee joint of the brace arm sections 16 and 17. The gambrel, with its arms 10 in the open or distended position, is adapted for supporting a carcass by engaging the hooks 11 in the legs of the same. If separate portions of beef or meat are attached to the hooks 11 while the arms 10 are in the open position, it is obvious that the gambrel will tilt upon removing either portion of the beef. This renders it difficult to remove the beef from one hook and to return the same thereto. When the gambrel is to be used for support-

ing separate sections of beef, the arms 10 are collapsed so that they assume the substantially vertical position shown in Figure 4. This is accomplished by removing the locking pin 25 so that the knee joint between the brace arm sections 16 and 17 will break downwardly. The free end of the section 17 may now be readily disengaged from the shoulder 31 and the brace 15 will assume a depending vertical position. There is now practically no tendency for the gambrel to tilt when the load is applied to or removed from either hook 11.

It is to be understood that the form of my invention, herewith shown and described, is to be taken as a preferred example of the same, and that various changes in the shape, size and arrangement of parts, may be resorted to without departing from the spirit of my invention, or the scope of the subjoined claim.

Having thus described my invention, I claim:—

A gambrel comprising a pair of hook carrying arms pivotally connected near their upper ends, one hook carrying arm being provided with spaced shoulders, a brace arm arranged between the hook carrying arms and embodying sections, a downwardly breaking knee joint connecting the inner adjacent ends of said sections, means to lock the knee joint against opening movement, means for permanently pivotally connecting the outer end of one brace arm section with the adjacent hook carrying arm, the other brace arm section being provided at its free end with a notch to receive the adjacent hook carrying arm, the wall of the notch being adapted to engage over a selected shoulder.

In testimony whereof I affix my signature:
JULIUS A. AUBOL.
